(57) **CLAIM**

The ornamental design for an "animal welfare toy," as shown and described.

DESCRIPTION

FIG. 1 is a top, front, and left side perspective view showing my new design for an animal welfare toy.

FIG. 2 is a top plan view of the animal welfare toy shown in FIG. 1.

FIG. 3 is a front view of the animal welfare toy shown in FIG. 1, the rear view being a identical to the front view shown.

FIG. 4 is a left side view of the animal welfare toy shown in FIG. 1, the right side view being identical to the left side view shown; and,

FIG. 5 is a bottom view of the animal welfare toy shown in FIG. 1.

The broken lines are for illustration only and form no part of the claimed design.
